UNITED STATES PATENT OFFICE.

FRANCIS J. McLOUGHLIN, OF BROOKLYN, NEW YORK.

DESIGN FOR A ROSARY-MEDAL.

50,894.

Specification for Design.

Patented June 5, 1917.

Application filed April 19, 1916. Serial No. 92,302. Term of patent 14 years.

To all whom it may concern:

Be it known that I, FRANCIS J. McLOUGHLIN, a citizen of the United States, residing in Brooklyn, in the county of Kings and State of New York, have invented a new, original, and ornamental Design for a Rosary-Medal, of which the following is a specification, reference being had to the accompanying drawing, forming part thereof.

Figure 1 is a plan view of the obverse of the medal illustrating my new design.

Fig. 2 is a similar view of the reverse side.

I claim:

The ornamental design for a rosary medal, substantially as shown.

FRANCIS J. McLOUGHLIN.
